UNITED STATES PATENT OFFICE.

WALTER CLINTON ROCKENSTIRE, OF WATERVLIET, NEW YORK.

ROLLER SIDE BEARING.

Application filed August 2, 1926. Serial No. 126,414.

This invention relates to side bearings for railway cars, and has for its principal object to provide an improved construction of devices of the character described, wherein the bearing element, such as a roller, may be readily adjusted to various heights. A further object is to produce a structure wherein the bearing element is permitted to tip sideways to meet the tipping of the car body. 10 Other features of invention will appear from time to time as the following description proceeds.

In the drawings,

Figure 1 is a longitudinal section of a side bearing, constructed in accordance with my invention, with parts thereof shown in elevation.

Figure 2 is a transverse section taken on line 2—2 of Figure 1.

20 Figure 3 is a top plan view of the device shown in Figure 1.

Figure 4 is a view in perspective showing the top of one of the adjusting wedges.

25 Figure 5 is a bottom view of one of the adjusting wedges.

Figure 6 is a view in perspective showing the top of a roller support.

Figure 7 is a detail view of the roller.

Referring to the details of the embodiment 30 of the invention illustrated in the drawings, the same is shown as applied to a roller bearing element 10, having a curved support or base 11 upon which it rides so as to be automatically elevated when the cooperating 35 surfaces of the truck and bolster are moving relative to each other, as for instance in rounding curves. This feature of a curved support for a roller is well known in the art and is shown herein merely by way of an 40 illustrative embodiment of my invention, which may be equally applicable to any other suitable form of bearing element.

Referring to the means for adjusting the elevation of the bearing element, including 45 the support 11, the same comprises a pair of wedges 12—12 disposed within and at opposite ends of a hollow base member. This base member preferably has side walls opening at the top, and the several parts of the bearing are disposed therein. The wedges 12—12 have downwardly and inwardly inclined faces 15—15 which engage corresponding inclined faces 16—16 formed at opposite ends of the bearing support 11.

50 An adjustment screw rod 20 is arranged longitudinally adjacent the bottom of the

base member 13, and downwardly opening slots 21—21 are provided longitudinally of the bottom face of wedges 12—12 so as to accommodate the screw rod 20 in a suitable 60 manner. The arrangement is such that the wedges 12—12 rest upon the bottom of the base member 13 and operate to raise or lower the superimposed bearing support 11 by relative movement of the wedges toward and 65 away from each other.

Movement of the wedges is controlled by the screw rod 20, in the preferred form shown, this screw having right and left hand threaded portions 25 and 26 at opposite ends 70 thereof, each of said threaded portions engaging nuts 27 and 28 which are disposed in cooperating position in recesses 29 and 30 respectively, formed in the lower faces of the wedges 12—12. These nuts are adapted 75 to have close fitting engagement in their respective recesses so as to prevent their rotation when the screw 20 is rotated relative thereto, but the wedges are free to be lifted off the rod 20 and nuts 27 and 28 when desired. The screw rod 20 is provided with an end portion 31 extending beyond the end of the casing or base member 13, in position to be readily manipulated by suitable tools, such as a wrench, when it is desired to adjust the wedges relative to each other. As 80 will be seen from Figure 1, the screw rod passes through an enlarged opening 32 in an upright part 13^a at the end of the base member 13, and is provided with a collar 33 pinned thereon, which is adapted to engage the inner face of the part 13^a, while a nut 34 is threaded on the outer end of the screw rod 20. With this arrangement the nut 34 85 may be screwed tightly against the part 13^a 90 so as to draw the collar 33 into frictional engagement on the opposite side of the part 13^a and thus lock the screw against rotation. 95 When the nut 34 is loosened the screw rod 20 is then free to be turned in either direction 100 and move the wedges toward or away from each other through the medium of nuts 27 and 28, it being observed however that the relative position of the screw rod 20 with respect to the casing 13 is not materially 105 changed during the adjustment of the wedges.

Referring to the means for permitting the bearing element to tip sideways to meet the tipping of the car body, it will be observed 110 that the bearing parts 15^a—15^a of the upper surfaces 15—15 of wedges 12—12 are convex

in form, disposed longitudinally of the wedges, and are adapted to have cooperating engagement with concave bearing surfaces 16^a—16^a formed on the lower faces 16—16 of the bearing support 11. As will be seen from the drawings, the arrangement is such that the bearing support 11 with its roller 10 is provided with means for accommodating itself to various angular positions transversely of the axis of the roller.

The uses and operation of the device above described will now be clear to those familiar with the art. The bearing element and its support have arcuate cooperating bearing surfaces disposed longitudinally of the device, in the form shown the convex supporting surface comprising parts of the adjustable wedge members, as described.

While I have illustrated and described one particular embodiment of my invention, it will be understood that I do not wish to be limited to the exact construction shown and described, but that various changes and modifications may be made without departing from the spirit and scope of my invention.

I claim as my invention:

1. In a side frame bearing, a base, a bearing member, and adjustable supporting means for said bearing member comprising a pair of wedges disposed at opposite ends of said bearing member, said bearing member and said wedges having cooperating arcuate bearing surfaces curved in transverse section

and extending longitudinally thereof, and means for adjusting said wedges relative to each other.

2. In a side frame bearing, a base, a bearing member, and adjustable supporting means for said bearing member comprising a pair of wedges disposed at the opposite ends of said bearing member, said wedges having convex upper surfaces, and said bearing member having cooperating concave lower surfaces, each extending longitudinally thereof, and means for adjusting said wedges relative to each other.

3. In a side frame bearing, a base, a bearing member, and adjustable supporting means for said bearing member comprising a screw member disposed longitudinally of said base, a pair of nuts threaded in opposite directions on said screw member, a pair of wedges disposed at opposite ends of said bearing member and each provided with slots for said screw, and with recesses for receiving one of said nuts therein in non-rotating engagement, said wedges having convex upper surfaces, and said bearing member having cooperating concave lower surfaces each extending longitudinally thereof, whereby said bearing member may accommodate itself to lateral tipping of the car body.

Signed at Schenectady, N. Y. this 24th day of July, 1926.

WALTER CLINTON ROCKENSTIRE.
